United States Patent Office

Des. 185,775
Patented July 28, 1959

185,775

TISSUE DISPENSING CABINET

Frederic P. Plotkin and Philip Shore, Los Angeles, Calif.

Application December 24, 1958, Serial No. 53,906

Term of patent 14 years

(Cl. D4—3)

Fig. 1 is a perspective view of a tissue dispensing cabinet showing our new design;

Fig. 2 is a top plan view of the same;

Fig. 3 is a front elevational view;

Fig. 4 is a bottom view; and

Fig. 5 is a side elevational view taken from the right hand side of Fig. 3.

The dominant features of our design reside in the portions shown in full lines.

We claim:

The ornamental design for a tissue dispensing cabinet, as shown and described.
